UNITED STATES PATENT OFFICE.

STEPHEN PALMER, OF LANSINGBURG, NEW YORK.

DESIGN FOR A SASH-CORD-GUIDE FACE-PLATE.

SPECIFICATION forming part of Design No. 19,570, dated January 7, 1890.

Application filed December 14, 1889. Serial No. 333,822. Term of patent 7 years.

To all whom it may concern:

Be it known that I, STEPHEN PALMER, a citizen of the United States, residing at the village of Lansingburg, county of Rensselaer, 5 and State of New York, have invented and produced a new and original Design for Sash-Cord-Guide Face-Plates, of which the following is a specification, reference being had to the accompanying drawings, forming a part 10 thereof.

Figure 1 is a top plan view of the plate. Fig. 2 is a side elevation of the same attached to a guide-case.

The leading feature of my design consists 15 in the contour of the face-plate.

The general outline of the plate presents an elongated figure, the ends of which are each composed of equal straight lines B, joined to form equal angles C on the inner side of the

boundary outline at the points where the lines 20 join each other, thus forming at each end the outline of one-half of a regular polygonal figure. The boundary outlines, which connect such end outlines on each side of the plate, are made up of short straight lines b, joined 25 to form a connected series of portions of the outline of a polygonal figure similar to that figure partly formed by the ends of the plate.

What I claim as new, and desire to secure by Letters Patent, is—

The design for a sash-cord-guide face-plate 30 herein shown and described.

In testimony whereof I have hereunto set my hand this 12th day of December, 1889.

STEPHEN PALMER.
